UNITED STATES PATENT OFFICE.

ROY A. LUSK, OF NEW YORK, N. Y.

DESIGN FOR A MUSTARD-BOTTLE.

46,131.

Specification for Design.

Patented July 21, 1914.

Application filed December 26, 1913. Serial No. 808,915. Term of patent 14 years.

To all whom it may concern:

Be it known that I, Roy A. Lusk, a citizen of the United States, residing at the city of New York, borough of Manhattan, in the county and State of New York, have invented a new, original, and ornamental Design for Mustard-Bottles, of which the following is a specification, reference being had to the accompanying drawing, forming part thereof.

The figure is a side elevation of a mustard bottle illustrating my new design.

Among the dominating features of the bottle illustrated may be noted a short cylindrical neck *a* merging at its lower end into a flaring shoulder portion *b*, the outline of which is a compound or ogee curve, the upper portion *c* of which is on a larger radius than the lower portion *d*. Below the shoulder is formed a swell *e*, the outline of

which is an oval curve, the upper portion *f* of which is on a larger radius than the lower portion *g*. The oval curve just referred to is so inclined as to provide for the merging of the curve *g* into a straight body portion *h* which has a larger diameter than the diameter of the shoulder portion *b*. At the lower end of the straight body portion *h* is another swell portion *e'*, the outline of which is similar to that of the portion *e* but with the curve arranged in the reverse direction and merging into a base *i*.

I claim:

The ornamental design for a mustard bottle substantially as shown and described.

ROY A. LUSK.
